POWER APPARATUS.

1,250,914.

Specification of Letters Patent. Patented Dec. 18, 1917.

Application filed March 3, 1917. Serial No. 152,200.

To all whom it may concern:

Be it known that I, LESLIE R. McDONALD, a citizen of the United States, and resident of Montreal, Province of Quebec, and Dominion of Canada, have invented new and useful Improvements in Power Apparatus, of which the following is a specification.

This invention relates to apparatus for transmitting power and more particularly for transforming power from one form to another as from oscillatory power to rotary power or vice versa. The invention is herein illustrated as embodied in apparatus of the general character disclosed in my prior applications Sr. No. 104,095, filed June 18, 1916; Sr. Nos. 139,332; 139,333; 139,334, filed Dec. 28, 1916, and Sr. No. 139,448, filed Dec. 29, 1916, to which reference is hereby made for a more complete disclosure of the apparatus in general, but it is to be understood that the invention may be otherwise employed as will hereinafter more fully appear.

In apparatus of the general character referred to and in other power apparatus it frequently occurs, especially where the source of power is limited in amount, that the velocity of the apparatus varies inversely with the load. That is, as the load increases the velocity decreases and as the load decreases the velocity increases. Under many circumstances this is highly undesirable. For example, in operating a phonograph of the type employing a disk record the driving torque necessary to rotate the disk at a given velocity is greater when the stylus engages the disk near its outer periphery than when it has moved inwardly nearer the center of the disk, inasmuch as the radial arm of the resisting force decreases as the stylus moves inwardly. When employing a constant source of power the velocity varies inversely with the retarding force or load and as the stylus moves toward the center of the record the velocity of rotation increases owing to the decreasing load. Obviously, the same principle applies to the operation of machinery of higher power.

The principal object of my invention, therefore, is to provide a method and apparatus for compensating for the tendency of power apparatus to vary in velocity with variation in load. A corollary object is to vary the supply of power in proportion to the load so that the supply may at all times be maintained substantially equal to the load.

A further object is to attain the foregoing objects automatically by means responsive to the variations in load. A still further object is to provide automatic power regulation particularly applicable to vibratory apparatus of the type disclosed in my prior applications.

Other objects of the invention will be apparent from the following description and the accompanying drawings in which,—

Figure 1 is a side view of the apparatus with portions, including one of the vibratory members, broken away;

Fig. 2 is a longitudinal section of the apparatus taken on line 2—2 of Fig. 1; and

Fig. 3 is a longitudinal section of the apparatus taken on line 3—3 of Fig. 2.

A simple embodiment of my invention has been chosen for the purpose of illustration, this embodiment comprising in its entirety a frame member 1, vibratory members 2 and 3 arranged in the form of a tuning fork, an electromagnet 4 having pole pieces 6, a shaft 7 carrying a pulley 8, and a belt 9 engaging the pulley, the belt being tensioned by means of a spring 11.

The vibratory portion of the apparatus comprising arms 2 and 3 of the tuning fork member is similar to that disclosed in my earlier applications above referred to, as is also the construction of the electromagnet means for vibrating the tuning fork arms. The coil 4 of the electromagnet means is supplied with either alternately or intermittent pulsatory current of a suitable frequency as, for example, that of the ordinary sixty-cycle commercial alternating current, and the vibratory members are preferably tuned to vibrate in synchronism with the pulsatory current either at the current frequency or at a multiple of the current frequency.

The belt 9 may contact with the pulley throughout an angle either greater or less than 360°, the angle of contact herein illustrated being approximately 180°. It is branched at one end into two parts, 12 and 13, these parts being connected to the inner faces of the vibratory members 2 and 3 at 14 and 16. At the opposite end the belt is connected to the bracket 17 mounted on the frame 1, this connection being made through the medium of spring 11. As the vibratory members move apart the lower end (Fig. 3) of the belt is drawn downwardly against the

tension of the spring 11 and the pulley 8 is rotated in the direction of the arrow. As the vibratory members move together the tension on the lower end of the belt is released and the spring 11 retracts the belt. 5 As more fully described in my prior applications, the belt is so designed and so related to the pulley and vibratory members and the spring is so tensioned that the belt 10 slides comparatively freely over the pulley as it is being retracted by the spring 11. Thus the belt tends to rotate the pulley only in a clockwise direction and with the vibratory members vibrating at a frequency of 15 one hundred and twenty cycles per second, as when using sixty-cycle alternating current, the clockwise impulses imparted to the pulley by the belt follow each other in such close succession that the rotative torque applied to the pulley is substantially continuous. 20

This application is directed more particularly to the mechanism for regulating the velocity of the output shaft 7 and the torque 25 radius of the belt 9 as applied to the pulley 8 and shaft 7, it being understood that the working apparatus, of whatever nature, which it is desired to drive by means of the apparatus, is connected to the upper end 30 (Figs. 1 and 2) of the shaft 7. This mechanism is preferably constructed and arranged as follows: The shaft 7, which is mounted in the frame 1 in suitable bearings 18 and 19, is of square cross-section 35 throughout the major portion disposed between the bearings 18 and 19 and upon this square portion of the shaft is mounted the pulley 8, the latter having an axial opening of square cross section so that it snugly 40 fits the square portion of shaft 7 in such manner that the pulley may slide freely longitudinally of the shaft, but so that the pulley and shaft are at all times constrained to rotate together. While the effective speed 45 ratio between the pulley and belt and the effective torque radius of the belt as applied to the pulley may be varied in numerous ways within the scope of my invention, the most simple way comprises tapering the 50 pulley 8 and associating the belt with the pulley in substantially the same manner shown in the drawings.

The belt 9 is preferably not disposed in the plane which is perpendicular to the axis 55 of the shaft 7, but is preferably disposed angularly with respect to such a plane. In the drawings the lower end (Fig. 3) of the belt is disposed nearer the plane of the larger end of the pulley 8 than is the upper end of the belt which is connected through the spring 11 to the bracket 17. By virtue of this arrangement the torque 60 impulse applied to the pulley each time the vibratory members move apart is not exactly tangential to the pulley but is di-

rected at a slight angle to a plane perpendicular to the axis of the shaft, so that each impulse applied to the pulley has a small component directed longitudinally of the shaft and toward the larger end of the pulley. Thus the pulley is not only supplied with tangential components of impulses at a rate which results in a practical continuous rotating torque but longitudinal components of impulses directed toward the 75 larger end of the pulley are applied to the pulley at the same rate, which results in substantially a continuous force urging the pulley toward the lower end (Figs. 1 and 2) of the shaft 7. This longitudinal force is 80 preferably counteracted by means of a compression spring 21 surrounding the shaft 7 and extending between the large end of the pulley 8 and a collar 22 rigidly attached to the shaft, the spring 21 being so designed 85 as to balance the longitudinal force applied to the pulley by the belt under normal conditions of load as applied to shaft 7.

In the absence of the present invention the amplitude of vibration of the vibratory 90 members would tend to decrease as the load applied thereto through the medium of the shaft, pulley and belt is increased, this reduction in amplitude causing a decrease in velocity of the shaft 7. Conversely, as the 95 load decreases the amplitude of vibration of members 2 and 3 and consequently the velocity of shaft 7 would tend to increase. However, with the mechanism herein disclosed, as the load varies the pulley 8 is 100 caused to move longitudinally along the shaft 7 in such manner that the belt 9 moves longitudinally with relation to the tapered surface of the pulley 8, the pulley being caused to move longitudinally of the shaft 105 owing to the variation, with variation of load, of the longitudinal impulses above referred to.

As the belt travels from the smaller to the larger end of the pulley the torque radius 110 of the belt, that is, the average distance from the axis of the shaft to the belt, increases. At the same time the angular velocity of the pulley 8 and shaft 7 decreases with relation to the linear velocity of the belt 9 by virtue 115 of the increased torque radius. Moreover, the impulses applied to the pulley increase in magnitude as the load on the shaft 7 increases, and therefore the longitudinal components of the impulses increase with increase in load. As the longitudinal components of the impulses increase the pulley 8 is forced along the shaft 7 against the action of spring 21 until the increased tension of the spring is sufficient to balance the increased longitudinal force. Thus, it will be apparent that as the load increases the pulley 8 is forced along the shaft 7 against the action of the spring 21 so that the belt 120 moves relatively to the pulley toward the 125 130

smaller end of the pulley. This tends to increase the velocity of the pulley and shaft, thus compensating for the tendency of the velocity to decrease by virtue of the decrease in amplitude of vibration of members 2 and 3 as the load increases.

Obviously by shifting the position of collar 22 along shaft 7 and thereby varying the tension of spring 21, or by varying the angularity of the plane of the belt 9 with respect to a plane perpendicular to the axis of shaft 7, or by varying any one or more of the variable factors, the proportion of the movement of pulley 8 with respect to variation in load and consequently the proportion of variation in torque radius and relative velocity between the belt and the pulley may be caused to vary in equal degree with respect to the variation in load, thereby maintaining constant velocity throughout variation in load; or, if desired, the parts may be so constructed and arranged as to cause the velocity to increase more or less rapidly than the increase of load.

While I have described the present invention in connection with apparatus of the general character disclosed in my prior applications above referred to, it is to be understood that the invention may be employed in any situation where power is transmitted between a belt and a pulley, the invention being applicable in situations where the belt moves continuously in the same direction over the pulley instead of being reciprocated back and forth thereover. In applying the invention to apparatus in which the belt moves continuously in a single direction, as indeed in applying it to vibratory apparatus of the character herein described, the tendency of the belt to travel toward the larger diameter of the pulley and the resulting tendency to pull the pulley in the opposite direction along the shaft, must be taken into account in determining the amount of taper of the pulley, the tension of the shaft spring, the angularity of the belt with respect to the pulley, and the other variable factors.

Inasmuch as the present invention is concerned more particularly with the speed control mechanism, the other parts of the apparatus have been described only in a general way with the understanding that reference may be had to my prior applications for a disclosure of the theory of operation, construction and various modifications of the other parts of the apparatus.

What I claim is:

1. Power apparatus comprising a pulley, a belt contacting therewith so that power may be transmitted therebetween, and means responsive to the amount of power transmitted therebetween for varying the relative velocities of the pulley and belt in

proportion to variations in the amount of power transmitted.

2. Power apparatus comprising a pulley, a belt contacting therewith so that power may be transmitted therebetween, and means responsive to the amount of power transmitted therebetween for varying the effective torque radius of the belt as applied to the pulley in proportion to variations in the amount of power transmitted.

3. Power apparatus comprising one or more vibratory members, means for vibrating the members, driving means actuated by the members, and means responsive to variations in the power transmitted to the driving means for governing the velocity of the driving means.

4. Power apparatus comprising one or more vibratory members, means for vibrating the members, and driving means actuated by the members, the driving means having mechanism for automatically regulating the velocity thereof in proportion to the amount of power transmitted thereto.

5. Power apparatus comprising a shaft, a tapered pulley mounted on the shaft so that power can be transmitted therebetween, and a belt contacting with the tapered pulley so that power may be transmitted therebetween, the belt and pulley being relatively movable longitudinally of the pulley so that the position of the belt may be varied relatively to the pulley along the tapered periphery of the pulley, thereby varying the torque radius of the belt relatively to the shaft.

6. Power apparatus comprising a shaft, a tapered pulley mounted on the shaft so that power can be transmitted therebetween, a belt contacting with the tapered periphery of the pulley so that power may be transmitted therebetween, the pulley being movable longitudinally on the shaft so as to vary the position of the belt longitudinally of the pulley, thereby varying the torque radius of the belt relatively to the shaft.

7. Power apparatus comprising a driven member, a gradually tapered pulley connecting with the driven member, driving means, a belt connecting with the driving means and contacting with the tapered pulley so as to rotate the pulley when actuated by the driving means, and means for causing a relative change of position between the pulley and the belt longitudinally of the pulley, thereby causing the belt to contact with portions of the pulley of different diameters.

8. Power apparatus comprising a driven member, a gradually tapered pulley connecting with the driven member, driving means, a belt connecting with the driving means and contacting with the tapered pulley so as to rotate the pulley when actuated by the driving means, and means for

- controlling the longitudinal position of the belt relatively to the pulley so that the belt can be gradually advanced along the tapered surface of the pulley while rotating the pulley.
9. Power apparatus comprising a shaft, a tapered pulley mounted on the shaft so that power can be transmitted therebetween, power means, and a belt extending between the power means and said pulley, the belt contacting with the tapered periphery of the pulley and being arranged so that power can be transmitted between the said shaft and power means, the belt and pulley being relatively movable longitudinally of the pulley so that the position of the belt may be varied relatively to the pulley along the tapered periphery of the pulley, thereby to vary the speed ratio between the shaft and the power means.
10. Power apparatus comprising a shaft, a tapered pulley mounted on the shaft so that power can be transmitted therebetween, power means, and a belt extending between the power means and said pulley, the belt contacting with the tapered periphery of the pulley and being arranged so that power can be transmitted between the said shaft and power means, the belt and pulley being relatively movable longitudinally of the pulley so that the position of the belt may be varied relatively to the pulley along the tapered periphery of the pulley, and the belt extending from the pulley obliquely to a plane perpendicular to the axis of the pulley on at least one side of the pulley.
11. Power apparatus comprising a shaft, a tapered pulley mounted on the shaft, a belt contacting with the pulley so that power can be transmitted therebetween, and means responsive to the power transmitted between the belt and pulley for controlling the relative position of belt and pulley longitudinally of the pulley so that the relative position varies with the amount of power transmitted.
12. Power apparatus comprising a shaft, a tapered pulley mounted on the shaft so as to drive the shaft, driving means, a belt extending between the driving means and pulley, the belt and pulley being relatively movable longitudinally of the pulley so that the position of the belt may be varied relatively to the pulley along the tapered periphery of the pulley, and means responsive to the power transmitted from the driving means to the shaft through the belt and pulley for controlling the relative position of belt and pulley.
13. Power apparatus comprising a shaft, a tapered pulley mounted on the shaft so as to drive the shaft, driving means, a belt extending between the driving means and pulley, the belt and pulley being relatively movable longitudinally of the pulley so that the position of the belt may be varied relatively to the pulley along the tapered periphery of the pulley, and means responsive to the power transmitted from the driving means to the shaft through the belt and pulley for controlling the relative position of belt and pulley.
14. Power apparatus comprising a shaft, a tapered pulley mounted on the shaft so that power can be transmitted therebetween, a belt contacting with the periphery of the pulley so that power can be transmitted therebetween, the belt being so arranged as to urge the pulley longitudinally of its axis when power is transmitted, and means for yieldingly urging the pulley in the opposite direction.
15. Power apparatus comprising a shaft, a tapered pulley mounted on the shaft so that power can be transmitted therebetween, a belt contacting with the periphery of the pulley so that power can be transmitted therebetween, the belt being so arranged as to urge the pulley longitudinally of its axis when power is transmitted between the belt and the pulley, and means arranged yieldingly to oppose the longitudinal force imparted to the pulley by the belt.
16. Power apparatus comprising a shaft, a tapered pulley mounted on the shaft so that power may be transmitted therebetween, a belt contacting with the periphery of the pulley so that power may be transmitted therebetween, the pulley being mounted to move longitudinally of the shaft and the belt being arranged to urge the pulley along the shaft, and yielding means to counteract the longitudinal force imparted to the pulley by the belt.
17. Power apparatus comprising a shaft, a tapered pulley mounted on the shaft so that power may be transmitted therebetween, a belt contacting with the periphery of the pulley so that power may be transmitted therebetween, the pulley being mounted to move longitudinally of the shaft and the belt being arranged to urge the pulley along the shaft, and means including a coiled spring surrounding the shaft to counteract the longitudinal force imparted to the pulley by the belt.
18. Power apparatus comprising vibratory means, a shaft, a tapered pulley mounted on the shaft for rotating the shaft, a belt connecting with the vibratory means and contacting with the tapered pulley, means to tension the belt so that the pulley is continuously rotated as the belt is moved back and forth by the vibratory means, said pulley being longitudinally movable on the shaft and the belt being arranged to urge the pulley along the shaft as power is transmitted through the pulley to the shaft, the longitudinal force imparted to the pulley by the belt varying with the power trans-

mitted, and means, yieldingly counteracting the longitudinal force imparted to the pulley by the belt in such manner that, as the transmitted power varies, the longitudinal position of the pulley on the shaft varies, thereby varying the position of the belt on the tapered pulley.

19. Power apparatus comprising vibratory means, a shaft disposed transversely of the path of vibration of the vibratory means, a tapered pulley longitudinally movable on the shaft, a belt connecting with the vibratory means and contacting with the tapered pulley, means to tension the belt so that the pulley is continuously rotated as the belt is moved back and forth, the belt being so disposed with respect to the pulley that the transmission of power from the vibratory means to the shaft through the belt and pulley tends to move the pulley along the shaft so as to shift the belt along the tapered pulley, and means yieldingly to counteract the longitudinal movement of the pulley so that the speed and driving

torque of the shaft varies with the power transmitted.

20. Power apparatus comprising vibratory means in the form of a tuning fork, a shaft disposed longitudinally of the prongs of the tuning fork and in a plane normally intersecting the plane of the forks between the forks, a tapered pulley mounted on the shaft so as to slide therealong, a spring urging the pulley in one direction along the shaft, a belt connecting with the vibratory means and contacting with the tapered pulley, and means to tension the belt so that the pulley and shaft are continuously rotated by the vibration of the vibratory means, the belt being so disposed that the transmission of power through the belt and pulley opposes the action of the spring, whereby the pulley is shifted relatively to the belt in response to variation in the power transmitted.

Signed by me at Montreal, Canada.

LESLIE R. McDONALD.
